UNITED STATES PATENT OFFICE.

ALBERT D. GROVER, OF NEW YORK, N. Y., ASSIGNOR, BY MESNE ASSIGNMENTS, TO AUTOSALES CORPORATION, A CORPORATION OF NEW YORK.

COIN-CONTROLLED VENDING-MACHINE.

1,310,863.

Specification of Letters Patent.

Patented July 22, 1919.

Application filed December 17, 1914. Serial No. 877,647.

To all whom it may concern:

Be it known that I, ALBERT D. GROVER, a citizen of the United States, and a resident of New York city, in the county of New York and the State of New York, have invented certain new and useful Improvements in Coin-Controlled Vending-Machines, of which the following is a specification.

10 My invention relates generally to coin-controlled vending machines and has for its object the provision of a machine particularly adapted for use in theaters or like places where the size of the machine must 15 essentially be limited so as not to constitute an obstruction or hindrance.

The machine of my invention comprises several features of novelty which combine 20 to form a mechanism of small dimensions, simplicity of construction, certainty of operation, and capable of rejecting spurious checks or disks without danger of becoming clogged or disarranged.

One feature of my invention resides in a 25 new form of delivery mechanism for the goods or articles in the machine, which is thereby especially adapted to vend large packages as distinguished from the so-called penny theater machines which sell small 30 pieces of penny goods. In the broad aspect of my invention this new delivery feature comprises a plurality of movable members mounted independently of each other and each adapted, when in normal position, to 35 support a piece of goods. These movable or adjustable supporting members are controlled by a common actuating device which is adapted to move the supporting members, one at a time, into releasing position. In 40 the mechanical embodiment of my invention now best known to me, these goods supporting members are in the form of tiltable shelves arranged one above the other within the goods chamber of the casing, and having 45 pin-and-slot connections with a vertically slidable bar which has a step-by-step movement. At each operative movement, this bar trips one of the shelves, beginning with the lowermost, into releasing position, so 50 that the packages drop into a position for removal by the patrons.

Another feature characterizing my invention is the coin-controlled mechanism for the delivery device which actuates the goods

supporting members. This mechanism is 55 very simple in construction and operation, consisting merely of a hand-operated member which carries an adjustable connecting element. Normally this element is in an inoperative position, but is adapted to be 60 moved into engagement with the trip device by the deposited coin, whereby the hand-operated member becomes operatively connected with the trip device to cause delivery 65 of the goods. In the preferred form of my 70 invention I provide means for holding the connecting element in one or the other of its positions during the operation of the hand member. In this way I positively prevent accidental movement of the connecting element from inoperative to operative position, or vice versa.

A preferred construction embodying the several features of my invention is shown in the accompanying drawings in which—

75 Figure 1. is a front elevation with the front wall or door partially broken away to show the interior of the casing;

Fig. 2. is a side elevation of Fig. 1 looking from left to right;

Fig. 3. is a side elevation of Fig. 1 looking from right to left with a part of the casing broken away to show the actuating bar for the delivery shelves;

Fig. 4. is a top plan view with the casing 80 partly broken away to show the combined washer-tester and slot-closer;

Fig. 5. is a transverse cross section on line 85 5—5 of Fig. 1 looking in the direction of the arrows.

Fig. 6. is a front view of the interior of the machine with the delivery shelves removed;

Fig. 7. is a longitudinal cross section approximately on line 7—7 of Fig. 6, looking 90 in the direction of the arrows; and

Fig. 8. is a longitudinal cross section approximately on line 8—8 of Fig. 6, showing the actuating bar for the delivery shelves.

The casing shown in the drawings for enclosing the parts of the machine consists of two separable sections—a section 1, which is in the form of a shell having a main wall, a top and bottom, and sides, and a section 2, which is in the form of a plate preferably 100 provided with narrow peripheral flanges which overlap the edges of the shell 1 to 105 form a tight fool-proof closure. In the par-

ticular form of machine shown in the drawings, I have shown the plate 2 as the front of the machine, and the main wall of the shell 1 as the rear plate of the machine. It 5 is obvious, however, that the plate 2 may constitute the rear of the casing and the main wall of the shell 1 constitute the front plate of the casing. The operation of the machine is precisely the same in either case. 10 I will, therefore, have it understood that whenever I use the term "rear" and "front" as applied to the separable sections 1 and 2 of the casing, I use the terms merely in a relative sense.

15 The two sections which form the closed outer casing are separably connected together in any suitable manner, as by a hinge 3 at the bottom of the casing. The purpose of making the outer shell 1 separable from the plate 2 is to permit access to the interior 20 of the machine for refilling or examination of the inside mechanism. A suitable locking mechanism is provided for locking the two sections of the casing in closed position, so as to prevent unauthorized access to the 25 interior of the machine.

The rear section or outer shell 1 is provided with a vertical wall or partition 4 which forms with the plates 2 the magazine or goods department 5. As seen from 30 Fig. 5 the partition 4 has a rearwardly extending flange 6 which lies against the side 7 of the rear section 1, and a forwardly extending L-shaped flange 8 which terminates 35 at the front edge of the side 9 of the rear section 1. By means of these flanges, which are merely for convenience of construction, the partition 4 is securely mounted in place 40 within the casing. The L-shaped flange 8 constitutes the right side wall of the goods chamber 5 and also forms with the side wall 9 of the casing, the end chamber 10 in which, as will be presently explained, operates the actuating device for the goods supporting shelves.

45 It will be clear that the partition 4 constitutes an inner shell having its main wall separated from the main wall of the outer shell 1 by a narrow space or chamber 4' into which, as will later on be described, enters the deposited coin for operating the delivery mechanism. I have not deemed it necessary to show any particular fastening means for the inner shell or partition 4, as 50 that is merely a matter of skill for the mechanic. As shown in the drawings, the inner shell or partition 4 is removable or detachable. This separation of the inner and outer shells renders access to the mechanism 55 arranged in the narrow space or chamber 4'.

To the partition 4 are hinged a plurality 60 of goods-supporting shelves 11 which extend forwardly into the magazine 5. Only two of these shelves are shown in the drawings, but it is obvious that any suitable num-

ber may be provided. These shelves are tiltably connected to the partition 4 in any suitable manner, as by hinge-connections 12 and 13. The hinge-connections 13 include crank arms 14 and 14' which extend into the angular slots 15 and 15', respectively, in the vertical slideable bar 16 mounted for operation within the end chamber 10. The bar 16 constitutes the operating mechanism for the supporting and delivery 70 shelves 11. The bar 16 is guided in its vertical movement by fixed pins 17 engaging in the vertical slots 18 of the bar. The pins 17 are carried by the side wall 9 of the rear section 1. Additional guiding means may 80 also be provided in the form of a lug 19 extending forwardly from the bar 16 into guiding contact with the front door 2. Any suitable means may be provided for yieldably maintaining the bar 16 in its normal 85 position and also in its different operated positions. In the drawings I have shown the bar 16 provided with notches 20 in which operates the free end of a spring blade 21 secured to the back of the rear section 1 at 90 22. The number of notches depends, of course, upon the number of supporting shelves in the machine. As I have shown but two of these shelves, only three notches are required in the bar 16. The lowermost 95 notch 20 is to retain the bar in normal position, the second notch retains the bar in its first actuated position after tripping the first or lower shelf, and the top notch retains the bar in its second actuated position 100 after tripping the second or upper shelf.

It will be seen from Figs. 3 and 8 that when the shelves 11 and the bar 16 are in normal position, the crank arms 14 and 14' rest at the bottom of their respective slots 105 15 and 15'. If now the bar 16 be pulled down (by mechanism to be presently described) until the spring 21 engages the second or middle notch 20, the angular portion 110 of the slot 15 will rock the crank arm 14 of the lower shelf 11 sufficiently to throw the shelf from horizontal to vertical position, as shown in Fig. 7. This tripping of the shelf causes the package of goods supported thereby to drop to the bottom 23 of 115 the chamber 5. The bottom 23 is an angular plate secured to the front door 2 at 24 in any suitable manner. The lower portion 120 of the magazine 5 may be called the delivery chamber, for when the package of goods rests upon the bottom plate 23, it is in alignment with the delivery opening 24 formed in one side of the casing. The front door 2 is provided with an opening 25 through 125 which the patron can insert a finger to push the delivery package laterally through the opening 24.

130 It should be observed that during the first movement of the actuating bar 16, there is no movement of the second or upper shelf

11, because during that interval the crank arm 14' engages only the vertical or inoperative portion of the slot 15'. When the bar 16 is in its first operated position, the crank 5 arm 14 of the lower shelf rests at the base of the vertical or inoperative portion of the slot 15, while the crank arm 14' of the other shelf is at the base of the angular or operative portion of the slot 15'. Consequently 10 when the bar 16 receives its second operation, the position of the previously tripped shelf is not affected, but the second shelf is rocked or tripped into releasing position. When the bar 16 has reached the end of its 15 second movement, the head of the spring 21 rests in the top notch 20, while the crank arms 14 and 14' are at the upper end of their respective slots 15 and 15'. It will, of course, be obvious that with a greater number 20 of shelves the forms of the actuating slots in the bar 16 would be changed correspondingly, so that the shelves would be tripped successively by the successive operations of the bar 16, without affecting the 25 position of the tripped shelves.

It will be noted that the pin-and-slot connections between the bar 16 and the delivery shelves 11, not only lock the shelves in normal or supporting position, but also hold the 30 tripped shelves in their actuated position out of the path of the subsequently released packages. In this way there is no danger of the tripped shelves forming an obstruction to the free passage of the goods to the delivery chamber.

It will also be observed that the connections between the actuating device or bar 16 and the delivery shelves is not broken during the tripping of the shelves. Consequently, when the bar 16 is restored to normal position after all the shelves have been tripped, the shelves are automatically moved back to normal supporting position. This is an important advantage because it 45 enables the person in charge of the machine to restore the actuated parts to normal position by a single operation—namely, the shifting of the bar 16 back to normal position. It will, of course, be understood that the 50 connections between the goods-supporting shelves and the actuating member 16 may be of other form than the pin-and-slot connection shown by way of illustration. Any form of connection will do, so long as it does not become entirely separated or broken when the goods-supporting members move into releasing position. In referring to the 55 connections between the shelves 11 and the bar 16 as inseparable, I simply mean that 60 those members do not become operatively separated or disconnected from each other when they are in actuated position.

I will now describe the coin-controlled mechanism for operating the actuating bar 65 16. To the back wall of the rear section 1

is pivoted a lever 26 at 27. This lever has a portion 28 extending out of the right side of the casing through the slot 29 so as to be capable of operation by hand. The handle portion of the lever is bent forwardly, as 70 shown in Fig. 3 so as to render it readily accessible when the case is fixed to a support such as the back of a theater chair. The lever 26 is normally held against the upper end of the slot 29 by a spring 30 which 75 is connected to the lever 26 at 31, and to the casing at 32. The lever 26 is provided with a fixed lug 33 arranged in alinement with the coin-chute designated as a whole by S. The hand lever 26 is provided with an upwardly projecting extension 34 carrying a pin or stud 35 on which is pivoted the coin-controlled pawl 36. At its rear end the pawl 36 is provided with a lug 37 arranged in vertical alinement with the coin-chute S. 80 At its lower end the pawl 36 carries a forwardly extending tooth 38, which is adapted to engage in the recesses 39 formed at one edge of the bar 16, as best shown in Figs. 7 and 8. The pawl 36 normally hangs by 85 gravity in the position shown in full lines in Fig. 6. A stop pin 40 on the lever 26 limits the rearward movement of the pawl. At its lower rearward end the pawl 36 carries a rearwardly projecting pin 41 which 90 is in alinement with the fixed guide piece 42 secured to the back of the casing. The purpose of the guide piece 42 is not only to 95 guide the pawl in its inoperative and operative paths of movement, but also to retain 100 the pawl in whichever path it begins its movement, as will be presently explained.

The operation of the coin-controlled mechanism above described is as follows: Normally the hand lever 26 and the connecting 105 pawl 36 are in the position shown in full lines in Fig. 6. In this position of the parts it will be seen that the tooth 38 of the pawl is out of contact with the bar 16, and that the lug 41 is to the left of the fixed guide 110 piece 42. If the hand lever 26 is pulled down without the previous insertion of a coin, the pawl 36 will move in an inoperative path—that is to say, the tooth 38 will remain out of engagement with the lower 115 recess 39 in the bar 16. During this movement of the parts the lug 41 on the pawl 36 will travel to the left of the guide piece 42 and the pawl is thereby held locked against accidental movement toward the actuating 120 bar 16. Without the provision of some such locking means as the guide piece 42, it might be possible by shaking or striking the casing a sharp blow, to cause the gravity pawl 36 to rock forward into engagement with the 125 bar 16, which would result in the delivery of a package of goods without the deposition of a coin.

Let us now suppose that a proper coin has been deposited into the machine through 130

the coin-entrance slot 43, provided in the top of the casing in alinement with the coin-chute S. The deposited coin descends through the coin-chute S into the position 5 shown in dotted lines C in Fig. 6. It will be seen that the lug 37 of the swinging pawl 36 is normally in the path of travel of the coin, so that the descending coin strikes the lug 37 and forces the same laterally out of 10 the way. This causes a forward rocking of the pawl 36 sufficiently to bring the tooth 38 into one of the recesses 39 of the bar 16. This coin-actuated position of the pawl 36 is indicated in dotted lines in Fig. 6, and this 15 actuated position is the operative or connecting position of the pawl, because it thereby establishes an operative connection between the hand lever 26 and the actuating bar 16. The fixed lug 33 on the hand 20 lever 26 is so arranged with respect to the lower inner edge 44 of the coin-chute S, that the deposited coin is sustained in position by and between the lug 33 and the edge 44, as clearly seen from Fig. 6. When the hand 25 lever is pulled down after the deposition of a proper coin, the pawl 36 pulls the actuating bar down with it, because of the locking engagement between the tooth 38 of the pawl and one of the recesses 39 in the bar 30 16. The movement of the parts is so limited that when the hand lever 26 strikes the lower end of the slot 29, the bar 16 has been moved through the proper distance to cause tripping of one of the goods supporting shelves 35 11, as previously explained in detail. It will be seen from Fig. 6 that when the pawl 36 is in coin-actuated position, the lug 41 is thrown to the right of the guide piece 42. Consequently during the subsequent downward 40 movement of the pawl 36, the guide piece 42 holds the tooth 38 of the pawl in locking relation with the actuating bar 16. This absolutely prevents accidental disconnection between the bar 16 and the hand 45 lever 26 when the latter is operated after the deposition of a proper coin. When the lever 26 reaches the end of its movement the lug 41 is slightly below the guide piece 42. Upon release of the lever the pawl 36 immediately 50 swings to the rear, so that during the return movement of the pawl 36 the lug 41 travels along the left of the guide piece 42. To facilitate and insure this path of movement of the lug 41 during the return 55 turn of the hand lever 26, the fixed guide piece 42 is beveled at the lower end as indicated at 42'. It will be seen from this that during the return movement of the parts, the guide piece 42 compels the pawl 36 to travel in an inoperative path, and thus prevents accidental engagement of the tooth 38 with the bar 16, which remains in its actuated position.

The number of recesses 39 in the bar 16 60 depends, of course, upon the number of sup-

porting shelves 11, there being a recess for each shelf. After the first or lowermost shelf has been tripped, the second recess 39 comes into alinement with the engaging tooth 38 of the pawl 36, and at the end of 70 the next operation of the machine, the next recess in the series comes into proper position, as will be well understood by those skilled in the art. The gravity pawl 36 also acts as "coin-tester" by testing the deposited coin as to size and weight. If the deposited check or coin is of less than the prescribed diameter, the pawl 36 will either not be rocked at all or not sufficiently to cause engagement of the tooth 38 with the bar 16. 80 The position of such a deficient coin is indicated at C' in Fig. 6. Should the deposited coin be of insufficient weight the same result will occur as with the coin C'. The weight and position of the pawl 36 are so calculated 85 before-hand, that it takes a coin of predetermined size and weight to actuate the pawl into connecting position. It should be noted that when the hand lever 26 is pulled down after the deposition of a deficient coin or 90 check, the latter is automatically discharged or rejected out of engagement with the pawl and hand lever before the parts reach the end of their movement. As soon as the gap between the edge 44 of the coin-chute and the supporting lug 33 of the descending hand lever 26 has sufficiently widened, the coin or check falls to the bottom of the casing. And this automatic discharge of the 95 coin takes place with a good coin as well. 100

It will be apparent from the foregoing description of my new coin-controlled mechanism that I have provided a device of extreme simplicity of construction and operation, which performs several important functions which in prior constructions necessitated separate or additional devices. Thus, the coin-controlled mechanism of my invention, consisting of merely two members—a hand operated member and a coin 105 actuated member—not only affords connection between the hand operated member and the goods delivery mechanism, but it also tests the deposited coin as to size and weight, and furthermore effects the automatic discharge of the coin. 110

A suitable magnet M is provided to prevent the operation of the machine by magnetic disks. This magnet is so arranged that with the walls 45, 46 and 47 of the coin-chute S, it forms a passage-way for the deposited coin. A good coin passes from the position indicated in dotted lines at C² in Fig. 6 through the lower portion of the coin-chute formed by the walls 48—51 and 49—52, 120 down to the position indicated at C'. A magnetic check, however, is carried along by the magnet under the poles 55 against the fixed pin or stop 57, as indicated by the dotted line position C³ in Fig. 6. The stud 125 130

57 breaks the magnetic disk away from the pole tip 56 of the magnet and swings it out of the coin-chute.

To prevent the insertion of washers or 5 rings into the machine, I provide at the coin-entrance slot 43 a washer-catching device like that described and claimed in my copending application, Serial No. 781,072, filed July 25, 1918. The parts numbered 59 10 to 64 inclusive operate like the corresponding parts shown in the aforesaid copending application, and need not, therefore, be here referred to in detail. These various parts are secured to the underside of the top of 15 the casing by any suitable means, such as the bracket 63.

To the pin or stud 65 carried by the rear of the casing, is pivoted a lever 66, having arms 67 and 68. The arm 67 terminates 20 near the arm 59 of the lever 58, as shown in dotted lines in Fig. 4, but is normally held below the plane of movement of the lever 58 by a spring 69. The bar 16 carries at its upper end a lateral lug 70 in vertical alignment with the arm 68 of the lever 66. The distance between the lower end of the arm 68 and the lug 70 is such that when the bar 16 reaches the end of its final step by step movement to trip the last shelf, the lug 70 25 strikes the arm 68 and thereby throws the arm 67 upwardly into the path of movement of the arm 59 of the lever 58. This causes the lever 58 to become locked, so that the insertion of coins becomes impossible. 30 When the bar 16 is restored to its normal position the spring 69 restores the arm 67 into inoperative position. By thus establishing a controlling connection between the bar and the washer catching device, the latter is made to perform the additional function 35 of a slot closing device.

Any suitable form of lock may be used for locking the two sections of the casing together. For the sake of illustration, I have 45 shown in the drawings a lock comprising a base plate 71, which is secured to the back of the casing at the top thereof by means of screws 72 or otherwise. On the base plate 71, are mounted two slidable bolts 73 and 50 74 adapted to engage suitable co-operating parts on the front section of the casing.

While I have herein shown and described one particular embodiment of my invention, I wish to be understood that I do not intend 55 to be limited to the details herein set forth, as it is obvious that in its broad aspect my invention may be mechanically carried out in other ways than that shown.

Having thus described my invention, what 60 I claim as new and desire to secure by Letters Patent of the United States, is:

1. In a vending machine, a plurality of 65 movable members mounted independently of each other for normally supporting the articles to be vended, an actuating device for

said members, adjustable but inseparable connections between said members and said device for operating said members successively by successive actuations of said device to release the articles for delivery, said connections causing automatic movement of the actuated members into normal supporting position when said device is restored to normal or initial position, and hand-operated means for actuating said device. 70

2. In a vending machine, a plurality of pivoted shelves mounted independently of each other for normally supporting the articles to be vended, an actuating device for said shelves, operative connections between 80 said shelves and said device for tripping said shelves successively by successive actuations of said device to release the articles for delivery, said connections causing automatic movement of the tripped shelves into normal 85 supporting position when said device is restored to normal or initial position, and hand-operated means for actuating said device.

3. In a vending machine, a plurality of 90 movable members mounted independently of each other for normally supporting the articles to be vended, a slidable bar for actuating said members, adjustable but inseparable connections between said members 95 and said bar for operating said members successively by successive operations of said bar to release the articles for delivery, said connections causing automatic movement of the actuated members into normal supporting position when said bar is restored to normal or initial position, and hand-operated means for actuating said bar. 100

4. In a vending machine, a plurality of 105 movable members mounted independently of each other for normally supporting the articles to be vended, a vertically slidable bar, pin-and-slot connections between said members and said bar for successively operating said members by successive actuations of 110 said bar, whereby the articles or packages are released one at a time, and hand-operated means for actuating said bar.

5. In a vending machine, a plurality of 115 pivoted shelves mounted independently of each other for normally supporting the articles to be vended, a vertically slidable bar having pin-and-slot connections with said members, said connections being such that said shelves are tripped successively by successive actuations of said bar to release the articles for delivery one at a time, and hand-operated means for actuating said plate. 120

6. In a vending machine, a plurality of 125 movable members mounted independently of each other for normally supporting the articles to be vended, an actuating device for said members, adjustable but inseparable connections between said members and said device for operating said members succes- 130

- sively by successive actuations of said device to release the articles for delivery, said connections causing automatic movement of the actuated members into normal supporting position when said device is restored to normal or initial position, hand-operated means for actuating said device, and yieldable means for retaining said device in its successively operated positions.
- 10 7. In a vending machine, a plurality of movable members mounted independently of each other for normally supporting the articles to be vended, a slidable bar for actuating said members, adjustable but inseparable connections between said members and said bar for operating said members successively by successive operations of said bar to release the articles for delivery, said connections causing automatic movement of the actuated members into normal supporting position when said bar is restored to normal or initial position, hand-operated means for actuating said bar, and yieldable means for retaining said bar in its successively operated positions.
- 15 8. In a vending machine, a plurality of pivoted shelves mounted independently of each other for normally supporting the articles to be vended, a vertically slidable bar having pin-and-slot connections with said members, said connections being such that said shelves are tripped successively by successive actuations of said bar to release the articles for delivery one at a time, hand-operated means for actuating said bar, and yieldable means for retaining said bar in its successively operated positions.
- 20 9. In a vending machine, a movable device having a step-by-step movement, a plurality of goods-supporting members operable independently of each other, connections between said device and said members for actuating one of said members at each operation of said device to release the goods supported by said member, said connections being adapted to move the actuated members back into supporting position, and hand-operated means to actuate said device.
- 25 10. In a vending machine, a slidable bar having a step-by-step movement, a plurality of goods-supporting shelves pivoted independently of each other, connections between said bar and said shelves for tripping one of said shelves at each operation of said bar to release the goods supported by said shelf, said connections being adapted to move the actuated or tripped shelves back into supporting position, and hand-operated means to actuate said bar.
- 30 11. In a vending machine, a casing having a vertical goods-chamber and a delivery opening leading from said chamber, a plurality of movable members mounted within said chamber independently of each other to support the articles to be vended, actuating
- mechanism for said members, connections between said mechanism and said members for operating the latter successively, beginning with the lowermost member, by successive actuations of said mechanism to release the articles for delivery through said chamber to said delivery opening, said connections automatically restoring the actuated members into normal supporting position when said mechanism is restored to normal initial position, and hand-operated means for actuating said mechanism.
- 35 12. In a vending machine, a casing having a vertical goods-chamber and a delivery opening leading therefrom, a plurality of shelves pivoted within said chamber independently of each other to support the articles to be vended, a common actuating device for said members having a step-by-step movement, connections between said device and said shelves for tripping the latter successively, beginning with the lowermost shelf, by successive actuations of said device to release the articles for delivery through said chamber to said delivery opening, said connections being adapted to move the tripped shelves into supporting position, and hand-operated means for actuating said device.
- 40 13. In a vending machine, a casing having a vertical goods chamber, a delivery opening connected therewith, a plurality of shelves pivoted within said chamber independently of each other to support the articles to be vended, a vertically slidable bar arranged at one side of said chamber and having a step-by-step movement, connections between said bar and said shelves for tripping the latter successively, beginning with the lowermost shelf, by successive actuations of bar, whereby the articles are released one at a time for delivery through said chamber to said delivery opening, said connections automatically restoring the actuated shelves into normal supporting position when said bar is restored to normal or initial position, and hand-operated means for actuating said bar.
- 45 14. In a vending machine, a plurality of vertically arranged supports movable independently of each other and adapted to support the goods or articles to be vended, a common actuating member for said supports, connections between said member and said supports for normally holding said supports in supporting position and successively actuating the same into releasing position, beginning with the lowermost support, to release one article or piece of goods at a time, said connections being adapted to move the actuated supports back into supporting position, and hand-operated means for actuating said member.
- 50 15. In a vending machine, a plurality of vertically arranged supports movable inde-

pendently of each other and adapted to support the goods or articles to be vended, a vertically slideable bar having a step-by-step movement, connections between said bar and 5 said supports for normally holding said supports in supporting position and successively actuating the same to releasing position, said connections automatically restoring the actuated supports into normal supporting posi-

tion when said bar is restored to normal or 10 initial position, and hand-operated means for actuating said bar.

In witness whereof, I hereunto subscribe my name this 16th day of December, 1914.

ALBERT D. GROVER.
